Primary Examiner — Shannon W Morgan*Assistant Examiner* — Rodolfo Castro, Jr.(74) *Attorney, Agent, or Firm* — Troutman Pepper Locke LLP; Tim Tingkang Xia, Esq.(57) **CLAIM**

The ornamental design for a cover for a notebook computer as shown and described.

DESCRIPTION

FIG. 1 is a top, front and right side axonometric view of a cover for a notebook computer according to my new design; FIG. 2 is an enlarged top, front and right side view of the portion 2 of FIG. 1;

FIG. 3 is a top view thereof;

FIG. 4 is an enlarged top view of the portion 4 of FIG. 1; and,

FIG. 5 is a cross-sectional view thereof taken across line 5-5 of FIG. 4.

Broken lines illustrate portions of a cover for a notebook computer that form no part of the claimed design.

1 Claim, 5 Drawing Sheets(56)
